UNITED STATES PATENT OFFICE

153,296

DESIGN FOR A STEREOSCOPIC VIEWER

Mathias Kauten, New York, N. Y.

Application March 31, 1948, Serial No. 145,466

Term of patent 7 years

(Cl. D57—1)

To all whom it may concern:

Be it known I, Mathias Kauten, a citizen of the United States of America, in the State of New York, residing in New York City, have invented a new, original, and ornamental Design for a Stereoscopic Viewer, of which the following is a specification, reference being made to the accompanying drawing, forming part thereof.

Fig. 1 is a perspective view of a stereoscopic viewer in an open position as when in use, showing my new design;

Fig. 2 is an end elevation of the same in a closed position; and

Fig. 3 is an elevational view of the front portion of the article being disconnected from the disclosure in Fig. 1.

The essential features of my design reside in the parts shown in full lines.

I claim:

The ornamental design for a stereoscopic viewer, substantially as shown and described.

MATHIAS KAUTEN.
